(57) **CLAIM**

The ornamental design for a seamless bag filter housing, as shown and described.

DESCRIPTION

FIG. 1 is a top perspective view of a seamless bag filter housing showing our new design;

FIG. 2 is an elevated perspective view of the seamless bag filter housing;

FIG. 3 is a rear view of the seamless bag filter housing;

FIG. 4 is a left side view of the seamless bag filter housing;

FIG. 5 is a front view of the seamless bag filter housing;

FIG. 6 is a right side view of the seamless bag filter housing;

FIG. 7 is a top view of the seamless bag filter housing; and,

FIG. 8 is a bottom view of the seamless bag filter housing.

The broken line showing in the figures is included for the purpose of illustrating and forms no part of the claimed design.
